COMPRESSOR

Jacob G. Aldinger, deceased, late of West York, Pa., by William W. Aldinger, executor, Springfield, Pa., assignor to York Corporation, a corporation of Delaware

Application June 11, 1946, Serial No. 676,027

5 Claims. (Cl. 230—24)

1

This invention relates to compressors, and particularly to an unloading device therefor.

The invention is primarily intended for use in refrigeration compressors and will be described as so embodied, but without implying limitation of the invention to this field.

Refrigeration compressors commonly are of the trunk piston type, single acting with the inlet valve in the piston and the discharge valve in the head.

The suction or intake connection commonly leads to the crank case or to a port which leads through the cylinder wall to and through the side of the piston. Both constructions are known and the invention can be used with either.

To secure freely acting valves and large port areas the inlet valves in the piston and the discharge valve in the head are desirably of the light weight ring variety.

According to the invention the unloading valve also is of the ring type, and works in an annular groove which encircles the cylinder at the junction of the cylinder walls with the cylinder head.

This arrangement offers many advantages. The unloading valve seat has ports which are almost continuous and encircle the cylinder. Adequate port area may be had without difficulty because no severe limits are imposed on port width. The unloading passages from the ports to the intake are short. The valve can be forced from its seat by rotating a ring which encircles the cylinder. Means for rotating such rings are readily adaptable to various cylinder arrangements common in multi-cylinder compressors.

In this way a simple compact arrangement giving a large area with a short unloading path is had with no change in the inlet valve, and no impairment of its size, arrangement or action. In fact the inlet valve continues to function while the compressor is unloaded, so that gas is circulated and the cylinder is cooled.

The invention will now be described by reference to the accompanying drawings in which:

Fig. 1 is an axial section through one cylinder of a compressor embodying the invention, the plane of section being parallel to the axis of the crank shaft. The unloading valve is shown open. The compressor is one designed for use with one of the halogenated hydrocarbon refrigerants, in this example dichlorodifluoromethane.

Fig. 2 is a section on the line 2—2 of Fig. 1.

Fig. 3 is a fragmentary view similar to a portion of Fig. 1, showing the unloading valve closed.

Fig. 4 is a perspective view of the unloading valve and its actuating ring.

2

Fig. 5 is an indicator card taken on the illustrated compressor.

Fig. 6 is an indicator card from a similar compressor designed for ammonia.

5 Referring to Figs. 1-3, and particularly Fig. 1. The main housing is generally indicated by the numeral 11 and the cap by 12.

A cylinder liner 13 is removably mounted in housing 11 and is positioned by flange 14 which 10 fits against a shoulder in a seat formed for it in housing 11. The liner has inlet ports 15 which lead from the compressor inlet chamber 16.

The cylinder head proper is shown at 17 and is held to housing 11 by studs or bolts, one of 15 which appears at 18. The head seats in a gasket 19 and holds the liner in place in the housing 11. Thus the passage 21 above head 17 and within cap 12 is the discharge passage of the compressor.

20 As will readily be understood, Fig. 1 shows merely the end cylinder of a row of two or more, arranged "in line", so that chamber 16 is the inlet passage for all these cylinders and chamber 21 is the discharge passage for all of them. The head 17 is common to all the cylinders. This is a known construction.

25 The head 17 has an annular recess 22 to afford clearance for the inlet valve guard carried by the piston and hereinafter described. The discharge ports 23 lead from the recesses 22 between 30 annular seats 24, 25 for the ring valves 26. The seats 24, 25 are continuous and the ports are continuous except for the necessary bridges. The valves 26 are guided, and are limited as to lift by a guard spider 27 held to head 17 by a center bolt 28 and machine screws 29.

35 The head 17 has an annular groove 31 concentric with the cylinder liner and opposite flange 14 from which that portion of the head 17 is spaced, as shown. Guided in groove 31 is a ring valve 32, which is the unloader valve and controls unloading ports 33 leading through flange 14 from the working space within liner 13 to the inlet chamber 16. The middle annular area of the lower face of valve 32 is relieved or recessed as shown to provide two sealing rims which engage the upper face of flange 14 on opposite sides of ports 33.

40 Valve 32 is biased in a closing direction (downward) by three coil compression springs 34 housed in pockets formed in the valve. Any desired number of springs could be used. The valve is shown open in Fig. 1 and closed in Fig. 3. The valve may be forced open against the urge of the springs by three pins 35 which are longitudinally reciprocable in guide ways drilled in 45 50 55

the flanged upper portion of liner 13. Three pins are sufficient but more can be used. The pins are actuated in unison by inclined cams 36 on a ring 37 swiveled on the liner 13 between shoulders 38, 39.

The ring 37 is constructed with a gap 41 (see Fig. 4), so that it may be sprung to pass it over the lower shoulder 39. Once in place a bridge piece 42 is fixed in place with socket-headed screws, closing only part of the gap 41. The remainder of gap 41 receives a spherical lug 43 mounted on actuating plunger 44.

Plunger 44 obviously may actuate in unison the rings 37 of a plurality of aligned cylinders, but the invention is not concerned with that detail.

Plunger 44 is biased in unloading direction (to the right in Figs. 1 and 2) by a coil compression spring 45. It may be forced to the left by a piston 46 in cylinder 47 when pressure fluid is admitted to the cylinder through connection 48. Any preferred pressure fluid may be led to connection 48 and may be controlled in any preferred way.

In one commercial embodiment the pressure lubricating system of the compressor is connected to connection 48; so that the compressor unloads automatically as it stops, and will not be again loaded unless it has run long enough to develop an effective lubricating pressure. This is a known expedient in the art, but any control scheme may be used so as to adapt the unloading function to the needs of particular cases.

The piston and the inlet valve carried thereby are conventional and hence require only brief description.

The piston 51 is of the "hour glass" type with a piston pin 52 and two rings 53 above the pin and two below. Of the latter 54 is a ventilated oil ring and 55 is an oil scraping ring. In all positions of the piston the inlet ports 15 are below rings 53 and above ring 54.

As will be readily understood the parts 59 are struts, so that the spaces 56 communicate freely with space 57 beneath the piston head. The connecting rod 58 has an oil port 59. The crank 45 shaft and crank are conventional and hence are not illustrated.

The valve seat members 61 are inserts held in place by bolts, one of which appears at 62. The inserts have two sets of ring ports, with the usual bridges and seat rims for the ring valves 63. These valve rings are guided and confined by a guard ring 64, held to the inserts by machine screws, one of which appears at 65.

The guard ring 64 is designed to fill the recess 22 and the lower portion of the ports 23, so that clearance volume is reduced to the practicable minimum.

It should be observed that ports 33 are interrupted only to the extent necessary to afford guides for pins 35. Hence, the ports are of large area. As shown in Figs. 1 and 3, they can be, and are, notably short.

When the unloading valve is open the working space is in free communication with the inlet chamber 16 and the inlet valves 63 are free to act. Thus, gas surges as the piston reciprocates, but there is also some circulation, which brings the gas in chamber 16 into the circulatory flow and gives a better cooling effect.

Fig. 5 shows cards for the illustrated compressor operating on dichlorodifluoromethane. The cards are drawn superposed at the same scale. The full line A shows a cylinder operating fully loaded. The dot and dash line B shows

the card for a cylinder unloaded by opening the valve 32. It should be understood that this card was taken on a multi-cylinder compressor and that all other cylinders of the compressor except 5 the one in question were fully loaded. The area of the card is remarkably small. The dotted line C shows the same cylinder unloaded by blocking the inlet valve 63 wide open while operating with the valve 32 closed. As was the case with card 10 B, all other cylinders of the multi-cylinder compressor were operating fully loaded. As to all 15 three cards, the conditions as to speed and other modifying factors were identical. Observe that the area for card C is much larger than the area for card B and since the area of this unloaded card represents wasted work, the fact demonstrates the superiority of applicant's unloading valve.

Similar tests were made with ammonia, to 20 make sure that the results were attainable regardless of the refrigerant used. The compressor was similarly constructed, but was water-cooled and the lifts of the valves were designed for ammonia. Fig. 6, in which A', B' and C' conform to A, B and C in Fig. 5, shows that the advantage is smaller in the absolute sense with ammonia, but still appreciable, for card B' is smaller than C'.

What is claimed is:

1. In a compressor, the combination of a reciprocable piston; means forming a cylinder and a head therefor, the piston being reciprocable in the cylinder toward and from the head, and serving with said cylinder and head to enclose a working space, said cylinder and head being so formed as to afford at substantially their junction, and extending beyond the limit of piston travel, an annular space which encircles and communicates with said working space, said annular space being defined by at least two opposed walls one of which serves as a valve seat and is provided with an annular series of unloading ports and the opposite one of which is formed with an annular guide groove for guiding and shrouding an annular unloading valve in motion toward and from said valve seat; an unloading valve guided and always at least partially shrouded by said groove and adapted to close against said seat; means operable to open and close said unloading valve; and inlet and discharge valves for said working space.

2. The combination defined in claim 1 in which the inlet valve is of the ring type and controls ports in the piston and the discharge valve is of the ring type and controls ports in the head, and the lift of the unloading valve is greater than the lifts of either the inlet or the discharge valve.

3. The combination defined in claim 1 in which the means operable to open and close the unloading valve comprise spring means biasing said valve in a closing direction, a cam ring encircling said cylinder, thrust members shiftable by the partial rotation of said cam ring and adapted when so shifted to force the unloading valve into its shrouding groove and away from its seat, and means for rotating the cam ring in reverse directions sufficiently to actuate said thrust members.

4. The combination defined in claim 1 in which the cylinder head is removable from the cylinder, the annular valve-shrouding groove is formed in the head and the annular space is defined at least in part by the head.

5. The combination defined in claim 1 in which the cylinder head is removable from the cylinder,

the annular valve-shrouding groove is formed in the head, the annular space is defined at least in part by the head, and the unloading-valve seat and its ports are formed on a portion of the cylinder.
